E. M. ERB

AIR HEATING UNIT

Filed Aug. 26, 1922

By *Edmund M. Erb* Inventor
Warren S. Ostow Attorney

UNITED STATES PATENT OFFICE.

EDMUND M. ERB, OF JERSEY CITY, NEW JERSEY.

AIR-HEATING UNIT.

Application filed August 26, 1922. Serial No. 584,440.

To all whom it may concern:

Be it known that I, EDMUND M. ERB, a citizen of the United States, and resident of Jersey City, in the county of Hudson and State of New Jersey, have invented certain new and useful Improvements in Air-Heating Units, of which the following is a specification.

The invention relates in general to an electrically energized heating unit designed to be inserted in a conduit for the purpose of heating air or other gases passing therethrough, and the present disclosure constitutes a division of my copending application, Serial No. 527,390, Hair drying apparatus, filed January 6, 1922.

In the above identified application it is suggested that cold air be supplied to a nozzle at the end of a flexible conduit and that means be provided in the nozzle for heating the air at will as it is discharged onto a person's head in the act of waving the hair thereon. It is required in hair dressing work that dry, hot air be supplied in large volume and that all portions of the air be uniformly heated otherwise a stream or core of cold air discharged with the hot air creates a very unpleasant sensation on the head of the person subjected to the drying treatment. On the other hand the nozzle must be manipulated rapidly from one side to the other of the person's head and any material weight in the heating elements which unnecessarily add to the weight of the large size nozzles used, is objectionable in that it is fatiguing to the operator to handle a large heavy nozzle.

Accordingly the primary object of the invention is to provide a heating unit for such nozzles which unit will be light in weight and at the same time provide sufficient heat dispensing surface to raise to the requisite temperature all of the air passing therethrough even when supplied in large volumes per unit of time.

Air passing through a conduit tends to form a cylindrical whirl about the axis thereof and accordingly the present disclosure features in connection with an air conducting nozzle of cylindrical form, a form of heating unit in which the heating

wire is disposed to follow the surface of a cone and in this way provides a heating element which will be spaced apart lengthwise of the axis of the air cylinder to give the requisite heat dispensing area and at the same time, when viewed in cross-section, will constitute a screen disposed uniformly across the entire cross-section of the cylindrical conduit and in this way insure the contact of all particles of the air with the heating wire at some point in the passage of the air column through the nozzle.

Another object of the invention is to provide a heating unit which may be readily inserted in the nozzle and which may be replaced by a similar insert without necessity of breaking permanent electric connection or mutilating either the nozzle or the unit.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:—

Figure 1 is a detail view taken axially through an air discharge nozzle and equipped with a heating unit constituting a preferred embodiment of the invention;

Figure 2 is a view of the insert shown in Figure 1 looking at the same from the right hand side; and

Figure 3 is a transverse sectional view taken on the line 3—3 of Figure 1 looking in the direction indicated by the arrows.

In the following description and in the claims, parts will be identified by specific names for convenience of expression but they are intended to be as generic in their application to similar parts as the art will permit.

In the drawings there is shown a flexible conduit 44 to the end of which is fitted a nozzle equipped with a heating unit 22 forming a preferred form of the invention.

The nozzle includes an open ended outer tubular shell 43 preferably formed of some

heat insulating material so that the nozzle may be handled without inconvenience to the operator. The discharge end of the nozzle is formed into a flaring end piece 45 preferably formed of metal. The heating device 22 constitutes an insert which can be fitted into the shell and readily removed therefrom as a unit to facilitate the repair or substitution of the same. The heater includes a 10 frame formed at the end adjacent the flexible section of a circular mounting ring or wheel 46 which has a snug fit in the shell; and is secured thereto by inset screws 47. The ring includes a diametrically extending bridge 15 piece 48 the center of which is enlarged to form a hub 49. The hub 49 constitutes a support for an axially positioned conducting rod 50, insulated from the hub by means of insulating bushings 51. One end of the rod 20 extends from the ring towards the flexible section and forms a binding post 52. The bridge 48 also carries a similarly mounted binding post 53. The opposite end of the rod 50 adjacent the discharge end of the 25 nozzle is provided with a head 54 secured to the rod by nuts 55 which also act as a binding screw. A plurality of flat mica plates 56 extend radially from the rod 50 as shown in Figure 3, are positioned between the 30 mounting ring 46 and the head 54 as shown in Figure 1 and are each of triangular form. The free edges 56' of each of the mica plates are provided with longitudinal spaced notches 57. A heating conductor 59 in the 35 form of a wire having high resistance is connected at one end to the binding post 53, is wound spirally and in the form of a cone about the edges of the plates from the mounting ring to the head. The outer end 40 of the wire 59 is connected to the binding screw 55 and the circuit is completed back to the binding post 52 through the conducting rod 50 which for this purpose is formed of metal. It is noted that the conical formation of the heating wire spaces the turns of 45 the wire not only along the length of the conduit considered axially of the shell as shown in Figure 1 but also spaces the turns when considered radially of the axis as 50 shown in Figures 2 and 3. In this way air spaces 58 are formed in the screen which may thus be considered as extending entirely across the bore of the shell. In this 55 way there is provided a free passageway for the air but all parts of the air will necessarily come in contact with or pass relatively close to some part of the hot wire before the air is passed from the nozzle.

While I have shown and described, and 60 have pointed out in the annexed claims, certain novel features of my invention, it will be understood that various omissions, substitutions and changes in the form and details of the device illustrated and in its operation may be made by those skilled in the

art without departing from the spirit of the invention.

Having thus described my invention, I claim:

1. A heating unit constituting an insert 70 adapted to be placed in a gas conduit to heat the gas as it is passed therethrough, said unit including a frame formed of a circular mounting ring having a diametrically extending bridge piece, an axially positioned conducting rod secured to and insulated from the bridge piece, with the end adjacent the bridge constituting a binding post, a coil of heating wire wrapped spirally about the rod and with one end of the wire 80 connected electrically to the rod at the end opposite the bridge piece and a second binding post carried by the bridge and connected electrically to the other end of the heating wire. 85

2. A heating unit including a centrally disposed electric conducting rod, means for supplying electric current to the rod, a plurality of plates extending radially of the rod and spaced apart circumferentially thereof, a heating wire connected electrically to the rod at the opposite end and wrapped spirally about the outer edges of the plates and means for supplying electric current to the end of the wire opposite the end connected to the rod. 90

3. An air discharging nozzle including a heat insulating tubular shell constituting a handle for holding the nozzle and air heating means positioned in said shell, said heating means including a screen of electric conductors capable of being heated when electric current is passed therethrough, said conductors being spaced apart considered transversely of length of the nozzle to permit the air to pass therethrough as it is discharged from the nozzle and spaced from the handle to maintain an air space in the nozzle between the heating means and heat insulating handle. 100

4. An air heating device including a circular mounting ring provided with a binding post, a conducting rod extending axially in one direction from the ring, a support carried by the rod, a conductor wrapped spirally about the support and connected at one end to the conducting rod and connected at the other end to said binding post. 115

5. In a device of the class described, the combination of a rod, a plurality of plates extending radially from said rod, said plates each converging in width from one end to the other, said plates provided with notches on their free edges and a conducting wire wound spirally about the plates and engaging in the notches. 120

6. A heating unit adapted to constitute an insert for a conduit to heat gases passing therethrough, said unit including a conducting element, and a long open frame includ- 125

ing partitions adapted to coact with the conduit to provide lengthwise passageways for the gas to be heated, a heating wire wrapped spirally about the frame along the length thereof and a pair of binding posts secured to said frame, confined within the longitudinally projected outlines thereof connected electrically to the ends of the heating wire and one of said binding posts constituting

an extension of the conducting element of 10 the frame.

Signed at New York city, in the county of New York and State of New York, this 18th day of August, A. D. 1922.

EDMUND M. ERB.
